UNITED STATES PATENT OFFICE.

ALFRED C. CROCKER, OF CHAGRIN FALLS, OHIO.

CHAIN AND PLUG HOLDER FOR BATHTUBS AND BASINS.

Application filed December 14, 1926. Serial No. 154,743.

This invention relates generally to bath tubs and basins and has more particular reference to a means whereby the chain and plug of a bath tub or basin may be properly supported when the plug is not in use, and this without requiring the hanging of the chain over the faucet or over side of the tub and the basin which interferes with the proper operation of the faucet or results in the scratching or other marring of the porcelain surface of the tub or basin.

An important object of the invention is to provide a holder of this character that may be readily associated with the usual overflow plates of bath tubs or basins without in any manner whatever altering the overflow plates or the means provided for securing the same in position upon the overflow opening of the tub or basin.

A still further and important object is to provide a holder of this character wherein the plug carrying chain may be easily secured within the holder or as readily removed therefrom when it becomes necessary to employ the plug when filling the tub or basin.

Other objects will become apparent as the nature of the invention is better understood, the same comprising the novel form, combination, and arrangement of parts hereinafter more fully described, shown in the accompanying drawing and claimed.

In the drawing wherein like reference characters indicate corresponding parts throughout the several views:

Figure 1 is a fragmentary view of the front side of a bath tub or basin equipped with a plug and chain holder constructed in accordance with the present invention, the same being shown as actually supporting the chain and plug.

Figure 2 is a vertical section thereof, and

Figure 3 is a perspective of the holder, per se.

Now having particular reference to the drawing, 5 indicates a bath tub or basin having at its front wall and adjacent its top side the usual overflow opening 6 in front of which is arranged the usual overflow plate 7 having openings 8 therein. Such overflow plates 7 are usually secured in position upon said opening 6 by threaded bolt 9 secured at its inner end within a web at the inlet end of the overflow drain pipe 10 and upon the outer end of which is threaded an ornamental thumb nut 7 that has an opening in its un-

der side to permit of the attachment of the plug carrying chain 11 to a projecting pin 12 upon the outer end of said threaded bolt 9.

My invention per se consists of a pair of relatively small metallic plates 13—13 that are welded or otherwise joined together and formed centrally with registering openings 14 whereby the same may be supported upon the projecting end of the bolt 9 and said thumb nut 10 is removed therefrom. Depending from the periphery of these plates 13—13 are slightly outward bent spring tongues 15—15 that are separated throughout their major portion of the length, while the lower ends have contact with each other for normally closing the lower end of the space between said tongues. The extreme lower ends of the tongues, may be, and preferably are, turned upon themselves to provide rounded abutments 16—16 to facilitate the easy disposition of one of the links of the chain 11 therebetween when it is desired to support said chain as well as the plug 11' above the bottom wall of the tub or basin.

It will thus be seen that I have provided a highly novel, simple, efficient chain and plug holder for bath tubs, basins, and the like that is well adapted for all the purposes heretofore designated, and even though I have shown and described this holder as consisting of a certain detail structure it is nevertheless to be understood that some changes may be made therein without effecting the spirit and scope of the appended claims.

Having thus described the invention, what I claim as new is:

1. In combination with a chain having a stopper secured on its lower end, and a bolt to which the other end of the chain is fastened, of means supported on the bolt for engagement with the links of the chain to hold the stopper carrying end thereof in a suspended position.

2. In combination with a chain having a stopper secured on its lower end, and a bolt to which the other end of the chain is fastened, of means supported on the bolt for engagement with the links of the chain to hold the stopper carrying end thereof in a suspended position, said means comprising a spring clasp including a body portion formed with an opening to receive the bolt, a pair of spring arms depending from the body portion, said arms being curved outwardly and then inwardly, the free ends of

the arms being disposed in contacting relation to provide a pair of opposed jaws through which the links of the chain may be passed.

5. 3. In combination with a chain having a stopper secured on its lower end, and a bolt to which the other end of the chain is fastened, of means supported on the bolt for engagement with the links of the chain to hold
10 the stopper carrying end thereof in a suspended position, said means comprising a spring clasp including a body portion formed with an opening to receive the bolt,

a pair of spring arms depending from the body portion, said arms being curved outwardly and then inwardly, the free ends of the arms being disposed in contacting relation to provide a pair of opposed jaws through which the links of the chain may be passed, the outer free ends of the spring 20 arms being bent back upon themselves to provide guide means for the links of the chain which pass between the jaws.

In testimony whereof I affix my signature.

ALFRED C. CROCKER.
